UNITED STATES PATENT OFFICE.

THOMAS COLLINS, OF BAINBRIDGE, NEW YORK, ASSIGNOR TO THE AMERICAN SEPARATOR COMPANY, OF BAINBRIDGE, NEW YORK, A CORPORATION OF NEW YORK.

CENTRIFUGAL LIQUID SEPARATOR.

1,426,959.

Specification of Letters Patent. Patented Aug. 22, 1922.

Application filed February 6, 1922. Serial No. 534,427.

To all whom it may concern:

Be it known that I, THOMAS COLLINS, a citizen of the United States, residing in Bainbridge, in the county of Chenango and 5 State of New York, have invented an Improvement in Centrifugal Liquid Separators, of which the following is a specification.

This invention relates to a centrifugal liquid separator and more particularly to 10 that type of such apparatus in which in conjunction with the bowl and superimposed liner plates or disks contained therein there is employed a centrally disposed feed 15 tube, a distributing device and a skimming cone. In separators of this type, as heretofore constructed, so far as I am aware, it has been customary to maintain the distributing device in position relatively to the 20 feed tube by the same devices employed to maintain the liner plates or disks in place. As is customary in separators generally the conically disposed liner plates or disks are spaced by separating lugs or ribs and as 25 heretofore associated with the distributing devices due to the unavoidable wear on these spacer ribs or lugs and the limited adjustment of the devices for connecting these parts the distributing devices, as well as 30 the liner plates or disks, become more or less loose and have the tendency to unbalance the separator. Obviously the wear on the spacer rib or lug on any liner plate or disk is relatively small, but in the aggregate 35 gate as many of these liner plates or disks are employed in each separator the adjustment of the devices for securing the parts in place is not sufficient to take up the wear inasmuch as the joints formed by the 40 connected parts must make a hermetically sealed closure. One of the objects of my invention is to overcome this difficulty and to so secure the distributing devices in place in the separator relatively to the base and 45 feed tube that the same is entirely independent of the liner plates or conically disposed nested disks.

In carrying out the invention the distributing devices are so constructed as to impart 50 and maintain the revoluble movement of the separator to the liquid prior to being distributed to the liner plates and thereby preventing the liquid from backing up into the feed tube. The feed tube is also so constructed as to cause the liquid to flow

through the same in such a manner as to prevent the flooding of the feed tube and the overflowing of the same. Furthermore the present invention also includes a cream regulating and discharge construction by 60 which the quantity and density or quality of the cream are controlled and its discharge facilitated by the revoluble motion, that is the centrifugal action of the apparatus. I 65 may also employ suitable devices for assisting the separator to be properly centered on the spindle upon which it revolves and to maintain its balance thereon, and all of these features will be hereinafter more particularly described.

In the drawing:

Fig. 1 is a central longitudinal section illustrating my improved centrifugal liquid separator.

Fig. 2 is a section on line 2—2, Fig. 1. 75

Fig. 3 is a partial elevation illustrating the features including the cream discharge.

Fig. 4 is a section through the upper end of the neck of the skimming disk also illustrating the cream discharge. 80

Fig. 5 is a plan of the distributing device.

Fig. 6 is a central longitudinal section of the distributing device.

Fig. 7 is a partial inverted plan of the 85 same.

Fig. 8 is a partial section illustrating another form of construction of the base of the distributing device, and

Fig. 9 is a partial section showing a form 90 of rib which may be employed on the exterior of the feed tube.

Referring to the drawings and particularly to Figs. 1 to 7 inclusive, the apparatus made in accordance with this invention preferably comprises a base 10, a bowl 11 and a cap nut 12 such as are customarily employed in similar structures in this art. The base 10 preferably includes an internal flange 13 with a conically disposed face 14 and a hub 15. The hub 15 is adapted to rest upon a flange 16 provided therefor at the lower or inner extremity of a feed tube 17. In a suitable position this feed tube 17 is provided with a partition wall 18 and is fitted with 105 a sleeve 19 adapted to surround a spindle 20 upon which in operation the apparatus revolves. Also as is customary I may employ a pin 21 extending from the upper end of the spindle 20 into the partition wall 18 in 110

order to connect the parts in their prearranged positions and also a ball or spherical bearing 22 set in a recess provided centrally therefor in the upper end of the spindle and 5 adapted to contact with the under surface of the partition wall or to lie in a recess therein to assist in centering the parts and maintaining a proper balance of the apparatus while rotating. The feed tube is provided 10 with a plurality of spaced longitudinally extending ribs 23 on the outer surface thereof, the purpose of which will be herein-after described; and the feed tube is also provided with a plurality of longitudinally 15 extending ribs or wings 24 on the inner surface thereof in order to prevent the flooding and overflow of the feed tube in the operation of the apparatus.

Associated with the feed tube is a distributing device 25. This is adapted to fit over the feed tube and is provided with a conical base 26 adapted to bear against the face 14 of the conically disposed internal flange 13 of the base 10. The distributing device is 20 fixed in its revoluble relationship to the feed tube by a key 27, or otherwise, arranged between these parts. It will be understood, however, that while I have illustrated and prefer to employ the distributing device with 25 a base as described I do not wish to be limited to this particular construction as other forms may be employed to equal advantage. As illustrated, however, the peripheral flange at the extremity of the base of the distributing device as illustrated at 28 is adapted to lie within the side or flange 29 of the base 10 and to be engaged with an intervening gasket 30 by the extremity of the bowl 11. The bowl 11, as is also customary, is provided 30 with a pin 31 adapted to enter a slot 32 provided therefor in the flange 29 to insure the proper position of the bowl relatively to the base in assembling the parts.

The upper end of the distributing device 45 forms a sleeve surrounding and fitting the feed tube and at a predetermined distance from its upper or outer end the distributing device is of a materially larger interior diameter than the exterior diameter of the feed tube, as is indicated at 33 forming a shoulder 34. The ribs 23 on the exterior of the feed tube do not quite abut against this shoulder 34 and are of such an extent as to contact with the interior surface of the distributing device so as to provide longitudinal 50 passages 35 therein, extending from this shoulder 34 to the spaced discharge passages 36 in the base of the distributing device. In a position intermediate of the ends of 55 these passages 35 and preferably immediately above the partition wall 18 the feed tube is provided with ports 37 by which the liquid flows from the feed tube to the passages 35 and to and through the discharge 60 passages 36 in the base of the distributing

device, it being manifest that the liquid in flowing through these passages, due to the ribs defining the same, will acquire the revoluble motion of the apparatus and will have the same maintained while flowing through 70 the passages 36 making it unnecessary for the liquid to acquire this motion after being delivered from the distributing device and thereby effecting a material saving in power required to operate the separator. 75

Within the bowl, as is customary, I employ a plurality of liner plates 38 which are preferably of the nested conical type fitting over the conical base of the distributing device and superimposed upon each other. 80 These liner plates are fitted over shoulders 39 provided therefor on the distributing device, and each liner plate in a similar position is provided with holes 40 through which the liquid may pass from the space between 85 each set of liner plates to the space between the next succeeding set. The holes 40 in the liner plates are so placed that when the liner plates are in position on the distributing device the passages formed by these 90 holes are intermediate of the discharge ori-fices of the passages 36 and are preferably at the same radial distance from the center of the separator. The liner plates are also provided with spacer ribs or lugs 41 by 95 which the same are properly separated from each other. At the inner edge of each liner plate there is a recess 42, these recesses forming a cream passage 43 at or adjacent the outer surface of the distributing device. 100

This separator is of the type in which a skimming disk is also employed. The skimming disk is indicated at 44 and includes a neck 45 which extends and fits in the neck 46 of the bowl. At its upper or outer extremity the neck 45 terminates in an internal flange 47 which, as illustrated, does not extend sufficiently far to contact with the outer surface of the feed tube, although it may be made to contact with the outer 110 surface of the feed tube if so desired as this particular feature forms no part of my invention and is relatively immaterial. In suitable positions the neck of the bowl is provided with slots 48 for the discharge of 115 the skim milk.

Fitted in the upper end of the neck 45 of the skimming disk I employ a ring 49. This ring is preferably split and the ends thereof separated as indicated at 50 so as to be 120 spaced and to form a transverse diagonally disposed passage 51 for the discharge of the cream. The slotted portion of the ring is placed immediately behind a boss or reinforcement 52 on the outer side of the neck 125 45 which is adapted to fit in a slot 53 provided therefor in the neck of the bowl. In the reinforced portion 52 of the neck of the skimming disk there is a tapped opening in which is fitted a regulating plug 54 which 130

may be adjusted to position by being turned as is customary in the art. This plug 54 extends into the passage 51 and the faces at the ends of the ring are fitted with screw threads to receive the plug. In the reinforced portion 52 of the neck 54 there is also a cream discharge opening 55 extending through the same and communicating with the passage 51 above the plug 54 and in a position offset therefrom.

10 The parts of the separator as hereinbefore described are maintained in position by the cap nut 12 which is tapped to receive the screw threaded end of the feed tube and may be provided with recesses 56 to receive the lugs on a spanner wrench or other tool 15 to secure the cap nut in place and to also remove the same.

By reference to Fig. 8, it will be seen that 20 instead of placing the passages 36 at a relatively small acute angle to the axis of the separator and so placing the same that the orifices are intermediate of the holes in the liner plates, I may place these passages 36 25 at a relatively large acute angle to the axis of the separator and place them in such a position that they lie in substantially the same radial lines as the holes 40 in the liner plates in which structure, as will be 30 understood, the discharge orifices of the passages 36 are in line with the holes 40 but are appreciably below the same.

Also by reference to Fig. 9 it will be seen that the conical base 26 of the distributing 35 device may be continued upwardly in a direct line as indicated at 57 to its point of connection with the cylindrical wall of the distributing device in which construction there is a chamber 58 at the lower or inner 40 ends of the passages 35 to which the liquid from the passages 35 is delivered and from which the liquid thus delivered is caused to pass through ports or passages 59 in the cylindrical wall to the space beneath the 45 liner plates. These passages 59 are thus so placed that the discharge orifices thereof are substantially below the holes 40 in the liner plates. In this structure to maintain the revolute motion acquired by the liquid in 50 the passages 35 the lower ends of the ribs 23 are extended to form a triangular shape to conform to the cross section of the chamber 58. In this structure also the discharge 55 orifices of the passages 59 may be placed intermediate of the holes 40 in the liner plates if so desired.

It will now be understood that the distributing device is maintained in position by the engagement of the bowl therewith 60 through the feed tube and the cap nut and the parts are secured in their relative positions independently of the liner plates or disks and the skimming disk and cream discharge. Also that due to the passages 65 formed between the feed tube and distribut-

ing device the liquid acquires the revolute motion of the apparatus in flowing through these passages before being delivered to the liner plates and thus prevents the liquid from backing up into the feed tube. The 70 ribs employed on the inner surface of the feed tube prevent the liquid from flooding or overflowing the feed tube and that by the improved cream discharge the quantity and quality of the cream may be controlled and 75 its discharge facilitated by the action of the separator in revolving by means of the transverse and diagonally disposed passage through which the cream is caused to flow to the opening through which it is dis- 80 charged.

I claim as my invention:

1. In a centrifugal liquid separator, a bowl, a feed device, a distributing device, a plurality of liner plates, and means for securing the distributor device in its longitudinal position independently of the liner plates.

2. In a centrifugal liquid separator, a bowl shell, a base for the same, a feed device, 90 a distributing device, a plurality of liner plates, and means for securing the distributing device in position between the bowl shell and the base thereof independently of the 95 said liner plates.

3. In a centrifugal liquid separator, a bowl shell, a base therefor, a feed device, a distributing device, a plurality of liner plates, and means for connecting the bowl shell to the base through the distributing 100 device to secure the latter in position independently of the liner plates.

4. In a centrifugal liquid separator, a bowl shell, a feed tube, a distributing device associated with the feed tube, a plurality of 105 liner plates, and means for securing the distributing device in position through the bowl shell independently of the liner plates.

5. In a centrifugal liquid separator, a bowl shell, a base therefor, a feed tube, a distributing device associated with the feed tube and the base of the bowl shell, a plurality of 110 liner plates, and means for securing the distributing device in position relatively to the feed tube and base of the bowl shell through 115 the bowl shell and independently of the liner plates.

6. In a centrifugal liquid separator, a bowl shell, a base therefor having an internal flange, a feed tube, a distributing device 120 having a base adapted to fit over the internal flange of the base of the bowl shell, a plurality of liner plates, and means for securing the distributing device in position on the base of the bowl shell through the 125 bowl and independently of the liner plates.

7. In a centrifugal liquid separator, a bowl including a shell and a base, the said bowl having an internal flange with a conical inner face, a feed tube, a distributing device 130

- fitting over the feed tube and having a recessed base in which the internal flange of the bowl base is received, a plurality of liner plates, and means for securing the distributing device in position through the bowl shell independently of the said liner plates.
8. In a centrifugal liquid separator, a bowl including a shell and a base, the said base having a conically disposed internal flange, a feed tube, a distributing device associated with the feed tube and having a base in which there is a conical recess adapted to receive the conically disposed internal flange of the bowl base, the periphery of the base 15 of the distributing device fitting within the base bowl, a packing between the edge of the bowl shell and the adjacent portion of the base of the distributing device, a plurality of liner plates, and means for securing the distributing device in position through the said bowl shell independently of the liner plates.
9. In a centrifugal liquid separator, a bowl including a shell and a base, the said base having an internal conically disposed flange, a feed tube, a distributing device associated with the feed tube and having a base in which there is a conical recess adapted to receive the conically disposed internal 25 flange of the bowl base, a flange seat on the feed tube upon which the bowl base is supported, a packing between the bowl shell and the outer portion of the base of the distributing device, a plurality of liner plates, and 30 a cap nut to engage the feed tube and to contact with the bowl shell to maintain the distributing device in position independently of the liner plates.
10. In a centrifugal liquid separator, a bowl shell, a feed device, a distributing device, and means for securing the distributing device in its longitudinal position through the said bowl shell.
11. In a centrifugal liquid separator, a bowl including a shell and a base, a feed tube, a distributing device adapted to seat on the bowl base, and means for securing the distributing device in position relatively to the feed tube through the said bowl shell.
12. In a centrifugal liquid separator, a bowl including a shell and a base, a feed tube, the bowl base being supported on the said feed tube, a distributing device associated with the feed tube and adapted to seat on the bowl base, and means for securing the distributing device in position relatively to the feed tube through the said bowl shell and base.
13. In a centrifugal liquid separator, a bowl including a shell and a base, a feed tube, the bowl base being seated on the said feed tube, an internal flange in the bowl base, a distributing device associated with the feed tube and having a base adapted to be seated 65 on the internal flange of the bowl base, and means for securing the distributing device in position relatively to the feed tube through the said bowl shell and base.
14. In a centrifugal liquid separator, a bowl shell, a feed tube, a base for the bowl shell seated on the feed tube and having an internal conically disposed flange, a distributing device associated with the feed tube and having a conical base adapted to be seated on the internal conically disposed flange of the base of the bowl shell, and means for securing the distributing device in position through the said bowl shell.
15. In a centrifugal liquid separator, a bowl shell, a feed tube, a plurality of liner plates having openings in alignment therein, and a distributing device for conveying liquid from the feed tube and delivering the same beneath the lower liner plate and intermediate of the openings therein.
16. In a centrifugal liquid separator, a bowl shell, a feed tube, a plurality of liner plates having openings in alignment therein, and a distributing device associated with the feed tube for conveying liquid therefrom and delivering the liquid below the lower liner plate at substantially the same radial distance from the center of the separator as the said openings in the liner plates but intermediate of the said openings.
17. In a centrifugal liquid separator, a bowl shell, a feed tube, a plurality of liner plates having openings in alignment therein, and a distributing device surrounding the said feed tube with spaces between the same and the feed tube and passages at the base thereof for conveying liquid from the feed tube and delivering the same beneath the lower liner plate intermediate of the openings therein.
18. In a centrifugal liquid separator, a bowl shell, a feed tube, a plurality of liner plates each having openings in alignment therein, and a distributing device surrounding the said feed tube with spaces between the same and the feed tube and having a conical base in which there are passages leading from the said spaces so as to convey a liquid from the feed tube through the said spaces and passages and deliver the same beneath the lower liner plate intermediate of the openings therein.
19. In a centrifugal liquid separator, a bowl shell, a feed tube having ports therein and a plurality of longitudinally disposed ribs on the outer surface thereof, a plurality of liner plates having openings therein, and a distributing device at its upper end surrounding the said feed tube and bearing upon the ends of the said ribs, with that portion of the distributing device extending below the ends of the said ribs of larger diameter than the feed tube to provide spaces between the distributing device and the feed tube and defined by the said ribs.

for conveying liquid from the said feed tube to the lower portion of the distributing device where the liquid is permitted to flow through passages and to be delivered beneath the lower liner plate intermediate of the openings therein.

20. In a centrifugal liquid separator, a bowl shell, a feed tube having ports therein, a plurality of liner plates each having holes therein, a distributing device having a bore of different diameters, the smaller diameter at the upper end thereof being substantially the same as the outer diameter of the feed tube and the larger diameter providing a

space between the distributing device and 15 the feed tube, and a plurality of spaced longitudinal ribs on the outer surface of the feed tube dividing the said space into a corresponding number of passages, there being a similar number of passages through the 20 base of the distributing device by which the liquid from the feed tube is conveyed therefrom and delivered beneath the lower liner plate intermediate of the holes therein.

Signed by me this 3rd day of February, 25
1922.

THOMAS COLLINS.
